(**) Term: **14 Years**

(21) Appl. No.: **29/237,885**

(57) **CLAIM**

(22) Filed: **Sep. 8, 2005**

The ornamental design for a document feeder for electronic copying machine, as shown.

(30) **Foreign Application Priority Data**

Mar. 9, 2005 (JP) 2005-007031

DESCRIPTION

(51) **LOC (8) Cl.** 18-99

Mention is made of Japanese Design Application No. 2005-007034, filed Mar. 9, 2005, for which a U.S. counterpart application is being filed concurrently with this application, incorporated herein by reference.

(52) **U.S. Cl.** **D18/49**

FIG. 1 is a perspective view of a document feeder for electronic copying machine showing our new design;

(58) **Field of Classification Search** D18/36-41, D18/44-55; 222/DIG. 1; 271/3.14, 8.1, 271/226, 278; 355/97, 99; 358/1.1; 399/1-7, 399/16, 75, 81, 107, 130, 151, 361, 365, 399/367, 381-383, 388

FIG. 2 is a front plan view thereof;

See application file for complete search history.

FIG. 3 is a top plan view thereof;
